LOCKING DEVICE FOR FULL FASHIONED
KNITTING MACHINESKurt O. Waechtler and Herbert M. Suess,
Berlin, N. J.

Application January 27, 1934, Serial No. 708,574

4 Claims. (Cl. 66—127)

This invention relates to a locking device and more particularly to a locking device for a full fashioned knitting machine whereby the yarn carrier bars may be more effectively and accurately locked when reaching their final position of travel in either direction.

The principal object of the invention is to accomplish a wedging engagement between the yarn carrier and the locking device so as to positively lock the carrier bar accurately in its proper position and eliminate any subsequent displacement thereof due to the vibratory action of the yarn carrier bar.

Another object of the invention resides in the novel arrangement and association of the component parts of the locking device and the yarn carrier bars whereby the incoming yarn carrier bar may be accurately locked and an outgoing yarn carrier bar automatically released.

Besides the above our invention is distinguished in the design and correlation of the catches and walls of the notches in the yarn carrier bars whereby positive engagement is assured and the vibrating action of the yarn carriers utilized to create a wedging action therebetween.

With these and other objects in view the invention will be better understood from the following detail description taken in connection with the accompanying drawings, wherein:

Figure 1 is a perspective view of the invention removed from a knitting machine.

Figures 2, 3 and 4 are diagrammatic views illustrating the relative positions of the end of the catch and the notch of the yarn carrier.

Figure 5 is a front elevation of the locking device.

Figure 6 is an end elevation of the locking device.

Figure 7 is a sectional view on line 7—7, Figure 6.

Figure 8 is a sectional view on line 8—8, Figure 5.

Figure 9 is a sectional view on line 9—9, Figure 5.

Again referring to the drawings illustrating one of the many constructions of our invention, the details of which may be modified in many ways to meet production requirements, the numeral 1 designates a set of yarn carrier bars illustrated in this particular instance as three in number, hereinafter identified as an "inner" bar 2, an "intermediate" bar 3 and an "outer" bar 4. Each bar is provided with inclining end portions 5 and 6 and has arranged thereon adjacent each end portion a notch 7. Particular

attention is called to the fact that in this particular instance, each notch consists of an inwardly inclining wall 8 and an outwardly inclining shoulder 9, the inclination of the latter having a direct bearing upon an important feature of our invention hereinafter set forth.

Arranged at each end of the knitting machine to cofunction with the notches for the locking of the carrier bars and to cofunction with the inclined end portions for the automatic releasing of the carrier bars are a pair of locking devices hereinafter known as a "left" locking device 10 and a "right" locking device 11. As these locking devices are of identical construction, we will limit the following description to the "right" locking device.

The locking device consists of a bracket 12 fixed to a suitable part of the frame of the knitting machine and this bracket 12 supports a stationary shaft 13 upon which is rotatably mounted three blocks or heads 14, 15 and 16, one for each carrier bar. Each block has secured thereto a pin 17 engaged by a spring 18 that in turn is secured to a support 19.

Associated with each carrier bar is a catch 20 making three in number hereinafter identified as an "inner" catch 21, and "intermediate" catch 22 and an "outer" catch 23. The "outer" catch is adapted to coact with the notch of the "outer" bar to lock the same; the "intermediate" catch 22 is adapted to engage with the notch of the "intermediate" bar to lock the same and the "inner" catch 21 is adapted to engage with the notch of the "inner" bar to lock the same.

These catches are adjustably connected to the heads and for this purpose we provide each catch with a slot 24 through which passes a bolt 25 that has a screw thread engagement with one of the herein mentioned heads that are mounted upon the stationary shaft 13. This connection enables each catch to be adjusted toward and away from the notch of the carrier bar for regulating the point of interengagement of the end of the catch with the wall of the notch. Each catch has connected thereto an offset extension 26 having overlapping arrangement with an associated carrier bar so that an incoming associated carrier bar may raise a catch and release its carrier bar locked thereby.

More specifically stated, catch 21 has its extension 26 arranged in overlapping engagement with the "intermediate" bar 3, catch 22 has its extension arranged in overlapping engagement with the "outer" bar and catch 23 has its extension 26 arranged in overlapping engagement with

the "inner" bar. This arrangement enables incoming movement of the "outer" bar to release the catch 22 from engagement with the "intermediate" bar and an incoming movement of the 5 "intermediate" bar will engage the extension 26 of catch 20 for releasing the "inner" bar and upon incoming movement of the "inner" bar the extension 26 of catch 23 will be engaged for releasing the "outer" bar for outgoing movements. The 10 tapering or wedge shape formation of the ends of the carrier bars enable the same to have a cam action with the extensions 26 for the effective raising thereof for releasing the various catches. Attention is called to the fact that due to the 15 relative arrangement of the carrier bars there is always one bar at one end of the machine and two bars at the other. This arrangement makes it possible for the selective movement of the catches by the traveling bars for the automatic 20 releasing of the outgoing bars and the automatic locking of incoming bars.

A very important feature of our invention as clearly illustrated in Figures 2, 3 and 4 resides in the inclination of the shoulder 9 in relation to 25 the center of the shaft 13 and the inclined position of the catch so that the end wall 27 of the catch will initially engage the upper portion of the inclined wall when the carrier bar first reaches its limit of travel and any further tendency of the carrier bar to vibrate will be prevented due to the wedging action of the end wall 27 of the catch with the inclined shoulder 9. In other words, vibration of the carrier bar will cause the catch to move into tighter engagement 30 with the shoulder 9 until the catch is finally seated as shown in Figure 2 and when this has been accomplished, the jamming action between the catch and the wall of the notch due to the off center position of the catch in relation to the axis 35 of the shaft 13 will rigidly lock the carrier bar in accurate position, thereby positively preventing 40 the production of inferior work or the breaking or jamming of certain knitting parts of the knitting machine.

45 It is, of course, to be understood that the notches may be given other formations than illustrated and component parts of the locking devices changed in many ways to meet manufacturing requirements and therefore we do not wish 50 to be limited in protection in any manner whatsoever, except as set forth in the following claims:

What we claim is:

1. In a knitting machine, a plurality of longitudinally travelling yarn carrier bars, a shoulder formed at each of the opposite end portions of the bars, each shoulder having a surface inclined downwardly in a direction away from the end portion of the bar in which said shoulder is formed, a pair of locking fingers associated with each bar and pivotally supported above the same, one finger of each pair being disposed for engagement with the shoulder at one end of the associated bar and the other finger of the pair being disposed for engagement with the shoulder at the other end of said bar, each finger slanting in a direction opposite to the direction of the inclination of the mentioned shoulder surface with which the respective finger is engageable so that the tip of the latter is directed towards said surface to abut thereagainst whereby, immediately upon engagement of a finger with its corresponding shoulder, a positive wedging action may be had therebetween to prevent jarring of the engaged carrier bar; means connected to said fingers and acting to normally urge the same into engagement with their respective carrier bars; means carried by each finger to extend in the path of travel of a carrier bar other than that with which the catch is associated and each bar having means disposed to act upon said first mentioned means for moving the catch out of locking engagement with its associated bar.

5 to extend in the path of travel of a carrier bar other than that with which the finger is associated and each bar having means disposed to act upon said first mentioned means for moving the catch out of locking engagement with its associated bar.

2. In a knitting machine, a plurality of longitudinally travelling yarn carrier bars, each bar having its opposite extremities provided with a camming face, a shoulder formed at each of the opposite end portions of the bars, each shoulder having a surface inclined downwardly in a direction away from the end portion of the bar in which said shoulder is formed, a pair of locking fingers associated with each bar and pivotally supported above the same, one finger of each pair being disposed for engagement with the shoulder at one end of the associated bar and the other finger of the pair being disposed for engagement with the shoulder at the other end of said bar, each finger slanting in a direction opposite to the direction of the inclination of the mentioned shoulder surface with which the respective finger is engageable so that the tip of the latter is directed towards said surface to abut thereagainst whereby, immediately upon engagement of a finger with its corresponding shoulder, a positive wedging action may be had therebetween to prevent jarring of the engaged carrier bar; means carried by each finger to extend in the path of travel of a carrier bar other than that with which the catch is associated for engagement with the camming face at the corresponding extremity of said other bar whereby, upon displacement of the latter, to move the finger out of engagement with its associated carrier bar for releasing the same.

3. In a knitting machine, a plurality of longitudinally travelling yarn carrier bars, a shoulder formed at each of the opposite end portions of the bars, each shoulder having a surface inclined downwardly in a direction away from the end portion of the bar in which said shoulder is formed, a pair of locking fingers associated with each bar and pivotally supported above the same, one finger of each pair being disposed for engagement with the shoulder at one end of the associated bar and the other finger of the pair being disposed for engagement with the shoulder at the other end of said bar, each finger slanting in a direction opposite to the direction of the inclination of the mentioned shoulder surface with which the respective finger is engageable so that the tip of the latter is directed towards said surface to abut thereagainst whereby, immediately upon engagement of a finger with its corresponding shoulder, a positive action may be had therebetween to prevent jarring of the engaged carrier bar; springs connected to said fingers and acting to normally urge the same into engagement with their respective carrier bars; means carried by each finger to extend in the path of travel of a carrier bar other than that with which the catch is associated and each bar having means disposed to act upon said first mentioned means for moving the catch out of locking engagement with its associated bar.

4. In a knitting machine, a plurality of longitudinally travelling yarn carrier bars, each bar having its opposite extremities provided with a camming face, a shoulder formed at each of the opposite end portions of the bars, each shoulder having a surface inclined downwardly in a direction away from the end portion of the bar in which said shoulder is formed, a pair of locking

5 fingers associated with each bar and pivotally supported above the same, one finger of each pair being disposed for engagement with the shoulder at one end of the associated bar and the other finger of the pair being disposed for engagement with the shoulder at the other end of said bar, each finger slanting in a direction opposite to the direction of the inclination of the mentioned shoulder surface with which the respective finger 10 is engageable so that the tip of the latter is directed towards said surface to abut thereagainst whereby, immediately upon engagement of a finger with its corresponding shoulder, a positive wedging action may be had therebetween to pre-

vent jarring of the engaged carrier bar; springs connected to said fingers and acting to normally urge the same into engagement with their respective carrier bars, means carried by each finger to extend in the path of travel of a carrier bar other than that with which the catch is associated for engagement with the camming face at the corresponding extremity of said other bar whereby upon displacement of the latter, to move the catch out of engagement with its associated 10 carrier bar for releasing the same. 5
